CLAIM

The ornamental design for a planer, substantially as shown and described.

DESCRIPTION

FIG. 1 is a reduced perspective view of a planer showing my new design, showing the front, top and one side thereof;

FIG. 2 is a side view taken from the right of FIG. 1; FIG. 3 is a side view taken from the left of FIG. 1; FIG. 4 is a top view thereof;

FIG. 5 is a bottom view thereof, the portions of the chain and gear not shown are understood to be identical to those shown.

FIG. 6 is a front view thereof; and

FIG. 7 is a rear view thereof.
